UNITED STATES PATENT OFFICE

JEAN BAPTISTE DURAND, OF MARSEILLE, FRANCE

COMPOSITION FOR FOUNDRY MOLDS

No Drawing. Original application filed April 4, 1930, Serial No. 441,709, and in France and Great Britain November 9, 1929. Divided and this application filed March 10, 1933. Serial No. 660,333.

The present invention is for a composition for foundry molds. This application is a division and continuation of my application Ser. No. 441,709 of April 4th, 1930, which also refers to my application Ser. No. 394,387 filed September 21st, 1929.

One object of the present invention is a composition comprising a subhydrated mixture of a hydraulic binder with artificial 10 sands of any composition having the property of becoming set when mixed with the hydraulic binder and having also the refractory property necessary for resisting the cast molten metal.

15 Another object of the present invention is a composition comprising a subhydrated material obtained by crushing the old molds made by the processes described in my aforesaid applications Ser. No. 394,387 and 20 441,709.

The mixtures whereof those molds are made can be re-used to great advantage in the making of other molds because:

(1) The binding agent forms a body much less resistant than if sufficient water had 25 been used to cause the whole of the binding agent to set, and hence the body is readily reduced by crushing to the fineness of sand; and (2) the binding agent, remaining subhydrated, has still an affinity for water and 30 the mixture therefore is capable of absorbing water and of partly setting, while still maintaining such a state of dryness that there is no need to stove dry the mold.

In thus re-using the material whereof 35 molds have been made according to the invention of my said prior applications, it is advantageous to use an additional quantity of binder; although it is possible to make a mold by the addition only of a proper quantity of water.

There are also to be considered as artificial 45 sands for the purpose of this invention, the materials obtained by crushing the materials as coal, cokes, lignite, talc, baryta, asbestos, etc. all substances sometimes useful for obtaining contact surfaces with the molten metal. It results from this, that the invention may be extended to molds having special 50 layers intended for surface contact with the poured metal, for instance by thin layers.

This action of the surface is intended for example to produce on the castings a peculiar surface aspect or a determined quality of the castings over a certain thickness.

In particular in casting iron objects the 55 layer directly in contact with the metal may be composed of a mixture of sands rich in carbon such as coke with cement, so as to offer to the molten metal a surface not only refractory but also resistant to decomposition, or of a composition different from that obtained by silicious or aluminous sands ordinarily used. The molds so obtained allow of realizing castings having a surface without scorifications and easy to free from sand. 60

65 The surfaces thus prepared need not generally be given a coat of paint, which renders the manufacture of molds very simple. In this case as it is not necessary to apply a coat of paint the layer forming the contact surface 70 may be less subhydrated than the composition constituting the mold provided that the latter is sufficiently subhydrated.

The surface layers of the mold should contain such a quantity of binding agent and 75 materials having such properties as will give in each case the special results desired. For example, the addition of carbon, such as coke, results in iron castings having non-scorched surfaces; the addition of coal non-freed from 80 gas results in obtaining crackled surfaces with an ornamental aspect; the addition of talc baryta, asbestos or magnesia gives very smooth surfaces. 85

In particular, where a protection layer is used the sand constituting the backing mass of the molds may be made of a natural or artificial sand of any kind. Even a sand of coarse grains may be used the effect being to increase the porosity of the mould. 90

What I claim is:

1. A composition for the manufacture of foundry molds consisting in a subhydrated agglomerate of sand of any species and of a hydraulic binder. 95

2. A composition for the manufacture of foundry molds comprising crushed molds made of a subhydrated agglomerate of sand and hydraulic binder.

3. A composition for the manufacture of 100

foundry molds consisting in a subhydrated mixture of fresh hydraulic binder and of crushed molds made of a subhydrated agglomerate of sand and hydraulic binder.

5 4. A mold for foundries consisting in a mixture of sand of any species, set hydraulic binder and non-set hydraulic binder, said materials being evenly distributed throughout the mass composing said mold.

10 5. A mold for foundries consisting in a mixture of an artificial sand having the properties of becoming set when mixed with hydraulic binder and of resisting cast molten metal, of set hydraulic binder and of non-set

15 hydraulic binder, said materials being evenly distributed throughout the mass composing said mold.

6. A mold for foundries consisting in a

mixture of crushed molds made of a subhydrated agglomerate of sand and hydraulic binder, of set hydraulic binder and of non-set hydraulic binder, said materials being evenly distributed throughout the mass composing said mold.

7. A mold for foundries in which the external parts of the walls thereof are constituted by an agglomerate of sand of any species and of a hydraulic binder and in which the internal parts of the walls of the mold are constituted by a less subhydrated agglomerate of a sand of any species and of a hydraulic binder.

In testimony whereof I have signed this specification.

JEAN BAPTISTE DURAND.
